Application December 31, 1934, Serial No. 759,982

18 Claims. (Cl. 101—378)

This invention relates to printing plate clamping or locking mechanism, and particularly to mechanism for clamping or locking the straight or longitudinal edges of arcuate printing plates to the plate or form cylinder of rotary printing machines.

In existing rotary printing machines, the curved or arcuate stereotype or electrotype printing plates are clamped or locked to the periphery of the printing or form cylinders, and particularly rotary newspaper printing machines, by arcuate clamp members or ring segments, and these arcuate clamp members are moved longitudinally or axially along the cylinders into locking engagement with the curved ends of the printing plates, thereby locking or clamping the opposed curved ends of each plate to its cylinder. The printing plates are further held against motion around the plate cylinders by margin bars which are secured on the peripheral portion of the cylinders and extend longitudinally thereof. When the plates are clamped to the plate cylinders, the straight longitudinal edges of the plates engage or abut the longitudinal edges of the margin bars, thereby preventing movement of the plates around the cylinders, but, however, the margin bars do not secure the plates against radial movement, such as may be produced by centrifugal force when the printing cylinders are rotated at relatively high operating speeds.

This method of securing the printing plates to the plate cylinders is commercially satisfactory when the printing presses are run at commercial speeds heretofore acceptable. However, there is a progressively increasing demand for higher operating speeds for rotary printing machines, and in designing rotary printing machines to meet this demand, it is necessary to provide additional securing or clamping means for each printing plate.

An object of my present invention is to provide means for clamping or locking the straight or longitudinal edges of curved printing plates to the plate cylinders.

A more specific object of this invention is the provision of means for locking or interlocking the straight or longitudinal edges of curved printing plates to the longitudinal edges of the margin bars positioned on the peripheral portion of the plate cylinders.

Another object of this invention is the construction and arrangement of the margin bars carried by the cylinders and the construction and arrangement of the straight or longitudinal edges of the printing plates so that they interlock to

secure the longitudinal straight edges of each printing plate to its plate cylinder.

A further object of this invention is the construction and arrangement of the margin bars positioned on the peripheral portion of the plate or form cylinders and the construction and arrangement of the straight or longitudinal edges of the curved printing plates for interlocking engagement, and the provision of means for moving the printing plates into interlocking engagement with the margin bars to thereby secure the longitudinal edges of each printing plate to its supporting cylinder.

An additional object of this invention is the provision of means for clamping or locking the straight or longitudinal edges of arcuate printing plates to the margin bars carried by the plate cylinders without interfering with the construction or operation of the conventional means for clamping the curved ends of the plates, thus permitting both the longitudinal edges and the curved ends of the plate to be clamped or locked to the plate cylinders to prevent the plates from being thrown off the cylinders by centrifugal force.

It is also an object of this invention to provide plate clamping mechanism of generally improved construction and arrangement, whereby the device will be simple, durable and inexpensive in construction as well as convenient, practical, servable and efficient in its use.

With the foregoing and other objects in view, which will appear as the description proceeds, the invention resides in the combination and arrangement of parts, and in the details of construction hereinafter described and claimed, it being understood that various changes in form, proportions and minor details of construction may be resorted to within the scope of the claims without departing from the spirit or sacrificing any advantages of the invention.

For a complete disclosure of the invention, a detailed description of a preferred and modified form thereof will now be given in connection with the accompanying drawings forming a part of this specification, wherein:

Figure 1 is a fragmental sectional view taken through a plate or form cylinder of a rotary printing machine with parts of the machine frame and operating components being shown in elevation, and the printing plates being depicted in locked or clamped position;

Figure 2 is a similar view, but showing one of the printing plates and its plate clamping mechanism in released position;

Figure 3 is a fragmental sectional view taken on the line 3—3 of Figure 1, and showing the end portion of a plate or form cylinder and components of the improved plate locking mechanism;

5 Figure 4 is a fragmental sectional view taken on the line 4—4 of Figure 1;

Figure 5 is a fragmental end elevation of a plate or form cylinder showing a modified form of plate clamping mechanism, parts appearing in 10 section, and the plate being shown in clamped or locked position;

Figure 6 is a similar view, but showing one of the plates and its plate clamping mechanism in released position;

15 Figure 7 is a fragmental end elevation, parts appearing in section, of a plate or form cylinder depicting another form of plate clamping mechanism, the plates being shown in clamped or locked position;

20 Figure 8 is a similar view, but showing one of the plates and its plate clamping mechanism in released position; and

Figure 9 is a fragmental end elevation of a plate or form cylinder, parts appearing in sections, depicting a further modified form of this 25 invention.

Referring to the drawings, in which similar reference characters designate corresponding parts, 30 indicates a plate or form cylinder to be employed in rotary printing machines, and peripheral portions of each plate cylinder 10 are cut away at its ends to provide recesses 11 for the reception of bearing blocks or plates 12 having spaced bearing apertures 14 formed therein, and 35 these bearing plates 12 are secured to the cylinder 10 by screws or other securing devices 13. In the form illustrated, the bearing plates 12 are positioned at diametrically opposed points on the periphery of the plate cylinder 10, at each end thereof, and each margin bar 15 is secured to the periphery of the cylinder 10 and extends longitudinally of the cylinder and overlaps the intermediate portion of each bearing plate 12. By this arrangement the bearing apertures 14 of 40 each bearing plate 12 are positioned at opposed sides of the margin bar 15 and are preferably spaced equal distances therefrom, as shown in Figures 1 and 2. Longitudinally extending shafts 16 are mounted for rotation or oscillation in the cylinders 10 by reducing the end portions of the shaft 16, as indicated at 17, and positioning the reduced end portion 17 in the bearing apertures 14 formed in the bearing plates 12. A lever 18 is secured to the reduced end 17 of each shaft 16, 45 and it is locked against rotation relative to the shaft 16 by means of a suitable key 19. The intermediate portion of each lever 18 has the enlarged head 20 of a stem or rod 21 secured thereto by means of a shoulder screw or bolt 22, which 50 extends through an aperture formed in the head 20 and is locked to the lever by a nut 24, thus permitting the head 20 of the link to turn about the bolt 22. Each stem 21 is slidably received within a sleeve or tubular member 26 having an enlarged rounded head 27 which is received within 55 a socket 28 formed in the shaft or extension 29 of the cylinder 10, and the inner portion of each socket is shaped to conform to the rounded head 27 of the sleeve 26, thus permitting rocking motion of each sleeve 26 within its socket 28. A helical extension spring 30 surrounds each sleeve 26 and the sliding stem 21, and one terminal of the spring engages the enlarged head 27 of the sleeve 26, and the opposed terminal engages the 60 enlarged head 28 of the stem 21, thereby exerting 65

a stress or tension on these heads tending to move the stem 21 outwardly. The outer terminal of each lever 18 has a roller 32 secured thereto by means of a shoulder bolt or screw 33, and the roller 32 is thereby engaged, in a phase of operation of the device, by a plunger 34 secured to a piston 35 slidably mounted in a cylinder 36 which is supported by the printing machine frame F. A helical extension spring 37 surrounds the plunger 34, and one terminal of this spring engages the 10 piston 35, and the opposed terminal engages a ring nut or annulus 38 threadedly secured to the end of the cylinder 36. The cylinder 36 is connected with a suitable source of fluid under pressure, not shown, through suitable pipes or conduits having their terminal fitting 39 screwed into the head 40 of the cylinder 36, thus providing means for forcing the piston outwardly against the influence or tension of the spring 37, as will hereinafter be more fully disclosed. 20

A centrifugal locking device is provided for cooperation with each lever 18, and each locking device includes a tubular bearing or sleeve 40' which is pivotally secured to the end of the cylinder 10 by a suitable shoulder screw 41, which extends through the sleeve 40' and is threaded into the cylinder at a point adjacent the free end of each lever 18. An arm 42 extends from each bearing sleeve 40', and is provided with an enlarged terminal head 43, and a finger 44 projects 30 from the tubular portion or member 40' and is positioned and arranged to engage the roller 32 of the adjacent lever 18 during a phase of operation of the device to be hereinafter disclosed. A stop member or stud 45 is threadedly secured to the 35 end of the cylinder 10 adjacent each arm 42 to limit the outward movement of the arm 42 in a position to cause the finger 44 to engage the roller 32 of the adjacent arm 18.

Apertures or recesses 48 are formed in the inner face of each curved or arcuate stereotype printing plate 49 to define shoulders 50, and a plurality of these apertures extend longitudinally of the plate and are positioned adjacent the longitudinal or straight terminals or edges of the 45 plate. The straight or longitudinal terminals or edges of the printing plates 49 are provided with beveled extensions 52, and these beveled extensions 53 cooperate with similar beveled extensions 53 formed on the margin bars 15 by undercutting 50 the longitudinal edge of these bars, as shown in Figures 1 and 2.

In order to forcibly move the beveled extensions 52 of the printing plates 49 into locking engagement with the beveled extensions 53 or 55 undercut portions of the margin bars 15, a plurality of pawls or fingers 55 extend radially from each shaft 16, and are arranged to project into the recesses 48 and engage their shoulders 50 when the shafts 16 are rotated by the outward movement of the lever 18 under the influence or tension of the springs 30. This movement forces the beveled projections 52 of the engaged printing plate under the beveled projections 53 of the margin bars 15 positioned at the opposed sides 65 of the plate, thereby securely locking the plate to the cylinder.

In operation, when it is desired to plate the plate cylinder 10, it is rotated to a "plating position", as shown in Figures 1 and 2, where the 70 selected rollers 32 are located immediately adjacent and below the plungers 34 of the pistons 35. While only one plunger has been illustrated at one side of each cylinder 10, it is to be understood, of course, that the plate locking mecha- 75

nism shown at the right side of each cylinder is to be duplicated at the opposed side, and the plunger actuating mechanism is also to be provided for the duplicated mechanism, but inasmuch as these devices are similar in construction and operation, only one set has been here illustrated. The cylinder 10 is stopped in this position, and the centrifugally actuated arms 42 drop to position indicated in Figure 2, thus permitting inward movement of the levers 18 and rollers 32. A suitable valve, not shown, is operated to admit fluid under pressure into the cylinders 36, which forces each piston 35 and plunger 34 outwardly into engagement with a roller 32 positioned in its path of movement, and continued movement of each plunger forces a lever 18 inwardly against the tension of a spring 30, thereby rocking the pawls or fingers 55 to plate releasing position, as indicated in Figure 2. The used plate 49 may then be readily removed and the new plate substituted. The fluid controlling valve is then manipulated to permit the springs 37 to withdraw the plungers 34 from engagement with the rollers 32, and their path of movement, thus permitting the springs 30 to force the engaged levers 18 outwardly, thereby moving the fingers or pawls 55 into the recesses 48 and into engagement with the shoulders 50 to force the beveled projections 52 of the engaged printing plate 49 into locking engagement with the beveled projections 53 of the margin bars 15. The cylinder may then be rotated approximately 180°, thus positioning the opposed plate so that it may be removed and a new plate substituted. After the plating operation, the cylinders are rotated to perform the usual printing operations, and the rotary motion of the cylinder causes the arm 42 and enlarged head 43 of each centrifugally actuated member to move outwardly until the arm 42 engages the stop stud 45. In this position the fingers 44 are positioned under the rollers 32, thus preventing the inward movement of the arms 18, thereby securely holding the plate clamping or locking components in locked position. This arrangement locks each plate 49 to the cylinder 10, because any tendency of the plate to be thrown off the cylinder by the action of centrifugal force is opposed by the interlocking extensions 52 and 53 of the longitudinal edges of the plate and the margin bars, and also by the pawls 55.

In the form of the invention depicted in Figures 5 and 6, levers 18a are secured to longitudinally extending shafts 16a, and these shafts have a plurality of pawls 55a secured thereto by inserting the pawls in suitable recesses 58 and securing them therein by screws or other securing devices 59. These pawls are constructed and arranged to project into the recesses 48a formed in the printing plates, and to engage the shoulders 50a to force the plate into locking engagement with the margin bar 15, as shown in Figure 5 and described in the form of invention depicted in Figures 1 to 4. A portion of each shaft 16a is provided with gear teeth 60, thus producing a gear segment, and these teeth 60 mesh with rack teeth 61 formed on a piston member 62, which is slidably received within a cylinder 63. A head or cap member 64 is provided for the cylinder 63 and is suitably secured to the printing cylinder 10, and a helical extension spring 65 is positioned within the piston 62 and one terminal of the spring engages the cylinder head 64 and the opposed terminal engages the piston 62, thereby causing the spring tension to force the piston inwardly to rock its shaft 16a

and move the locking pawls 55a into engagement with the shoulder 50a of the printing plate to move the printing plate into locking engagement with the margin bar. In order to release the selected printing plate, fluid from any suitable source, not shown, is admitted into the cylinder 63 under pressure, thereby forcing the piston 62 outwardly against the tension or stress of the spring 65, and this movement of the piston 62 rotates or rocks a shaft 16a sufficiently to withdraw the pawls 55a from engagement with the printing plate shoulders 50a, thereby releasing the plate, as shown in Figure 6, to permit its removal from the printing cylinder. A piston 62 is provided for each lever 18a, and the cylinders 15 63 are preferably positioned in different transverse planes, as indicated in full and dotted lines in Figure 5.

Another form of my invention is disclosed in Figures 7 and 8, in which form, levers 18b are secured to shafts 16b, and these shafts are mounted for rocking movement within the cylinder 10b, similar to the arrangement disclosed in Figures 1 to 5. The shafts 16b have pawls 55b suitably secured thereto, and these pawls enter recesses 48b formed in the printing plates and engage shoulder 50b, thereby moving the straight longitudinal terminals of the printing plate into locking engagement with the margin bars when the shafts are rocked to move the outer terminals of the pawls 55b toward the margin bars 15. A link 68 is pivotally secured to the outer terminal of each lever 18b, as indicated at 69, and the opposed terminal of each link 68 is pivotally secured to a block or nut 70, as indicated at 71. The block 70 has a threaded aperture formed therein for the reception of the threaded shaft or screw 72, and the inner terminal of this shaft is rotatably mounted in an antifriction bearing 73, and its opposed end is rotatably mounted in the bearing member or lugs 74. In order to rotate the shaft 72, a rectangular tool engaging head 75 is formed on the outer terminal thereof, and when a wrench or the tool is applied to the head 75 to rotate the shaft 72, the block 70 travels along the shaft 72. When the block 70 moves inwardly, motion is imparted to the levers 18b through the intermediation of the link 68, thereby causing the shafts 16b to move the pawls 55b into the recesses 48b and into engagement with the shoulders 50b to lock and release the printing plate as hereinbefore disclosed.

In the form of my invention which is depicted in Figure 9, the margin bar 15c is provided with beveled edges, the same as shown in the other disclosed forms, for interfitting engagement with the beveled straight edges of the printing plates, but each printing plate is provided with lugs or bosses 80 which extend inwardly from the inner face of the printing plate from a point adjacent the beveled longitudinal or straight edges thereof to provide shoulders 82. The lugs 80 are received within recesses 84 formed in the cylinder 10c, and the shoulders 82 of the lugs 80 are engaged by the pawls or fingers 55c to force the printing plate into locking engagement with the margin bars, as hereinbefore disclosed.

By the employment of applicant's invention, as disclosed in this application, the straight or longitudinal edges of commercial stereotype or electrolyte printing plates may be clamped or locked to the cylinder, and this clamping arrangement may be employed in conjunction with the conventional clamping mechanism, not shown, which engages and clamps the curved 75

ends of the plate. By applicant's disclosed arrangement, when employed with the conventional plate clamping mechanism, all the edges of each printing plate are clamped or locked to the cylinder, thereby permitting the cylinders to be rotated at relatively high operating speeds without the danger of centrifugal force throwing the plates from the form cylinders.

The extensions 52 formed on the longitudinal straight edges of the printing plates, and the overhanging projections 53 formed on the longitudinal edges of the margin bars are liberally proportioned to provide broad interfitting surfaces therebetween, and the clamping pawls are so disposed as to form positive dovetails between the underside of the margin bar projections 53 and the engaging faces of the clamping pawls when these pawls are in locking position, thereby securely locking the plates to the cylinders against either radial or tangential motion.

What I claim is:

1. In combination, a printing cylinder, margin bars on the cylinder, an arcuate printing plate, the straight edges of the printing plate and the longitudinal edges of the margin bars being constructed and arranged for interlocking engagement, and movable means for engaging and moving the plate transversely of the axes of the cylinder and the plate to force the straight edges of the plate towards the margin bars and into locking engagement with the longitudinal edges of the margin bars thereby securing the printing plate to the cylinder.

2. In combination, a printing cylinder, a printing plate having shoulders on the inner face thereof, bars carried by the cylinder and extending longitudinally thereof, and movable means for engaging the shoulders to move the plate transversely of the axes of the cylinder and the plate thereby forcing the straight edges of the plate towards the bars and into locking engagement with the said bars to lock the plate to the cylinder.

3. In combination, a printing cylinder, a printing plate having recesses formed therein, bars carried by the cylinder and extending longitudinally thereof, and movable means for engaging the recesses to move the plate thereby forcing the straight edges of the plate into locking engagement with the said bars to lock the plate to the cylinder.

4. In a plate clamping device, the combination with a printing cylinder, margin bars on the cylinder, and arcuate printing plates having shoulders formed on the inner face thereof, of means within the cylinder for engaging the shoulders to move the plate transversely of the axis of the cylinder to force the straight edges of the plate towards and into locking engagement with the margin bars thereby securing the plate to the cylinder.

5. In combination, a printing cylinder, a printing plate having recesses formed therein and a shoulder at one terminal of each recess, bars carried by the cylinder and extending longitudinally thereof, and movable means for engaging the shoulders to move the plate thereby forcing the straight edges of the plate into locking engagement with the said bars to lock the plate to the cylinder.

6. In combination, a printing cylinder, margin bars carried by the cylinder and extending longitudinally thereof, an arcuate printing plate having shoulders formed on the inner face thereof, the straight edges of the printing plate and longi-

tudinal edges of the margin bars being constructed and arranged for interlocking engagement, and means for engaging the shoulders for moving the plate transversely of the axes of the cylinder and the plate to force the straight edges of the plate towards and into locking engagement with the longitudinal edges of the margin bars thereby securing the printing plate to the cylinder.

7. In combination, a printing cylinder, margin bars carried by the cylinder, the longitudinal edges of the margin bars having projecting portions, an arcuate printing plate having projections extending from the inner portion of its straight edges, and means movable transversely of the axis of the printing cylinder for engaging and moving the plate toward the margin bars to move the projections of the plate under the projecting portions of the margin bars to thereby lock the plate to the cylinder.

8. In combination, a printing cylinder, margin bars carried by the cylinder, the longitudinal edges of the margin bars being undercut, an arcuate printing plate having projections on the straight edges thereof and shoulders formed on its inner face adjacent its straight edges, and movable means engaging the shoulders and moving the plate to move the projections into locking engagement with the undercut edges of the margin bars to thereby lock the plate to the cylinder.

9. In combination, a printing cylinder, margin bars on the cylinder, an arcuate printing plate, the straight edges of the printing plate and longitudinal edges of the margin bars being constructed and arranged for interlocking engagement, movable members operably supported by the cylinder for engaging and moving the plate to force the straight edges of the plate into locking engagement with the longitudinal edges of the margin bars thereby locking the printing plate to the cylinder, and means for locking the movable member in plate locking position.

10. In combination, a printing cylinder, margin bars on the cylinder, an arcuate printing plate, the straight edges of the printing plate and longitudinal edges of the margin bars being constructed and arranged for interlocking engagement, movable members operably supported by the cylinder for engaging and moving the plate to force the straight edges of the plate into locking engagement with the longitudinal edges of the margin bars thereby locking the printing plate to the cylinder, means for locking the movable member in plate locking position, and means actuated by the rotation of the cylinder for locking the movable member in plate locking position.

11. In combination, a printing cylinder, margin bars on the cylinder, an arcuate printing plate, the straight edges of the printing plate and longitudinal edges of the margin bars being constructed and arranged for interlocking engagement, movable members operably supported by the cylinder for engaging and moving the plate to force the straight edges of the plate into locking engagement with the longitudinal edges of the margin bars thereby locking the printing plate to the cylinder, means for locking the movable member in plate locking position, and centrifugally-actuated means for locking the movable member in plate locking position.

12. In combination, a printing cylinder, margin bars on the cylinder, an arcuate printing plate, the straight edges of the printing plate

and the longitudinal edges of the margin bars being constructed and arranged for interlocking engagement, movable members operably supported by the cylinder for engaging and moving the plate to force the straight edges of the plate into locking engagement with the longitudinal edges of the margin bars thereby locking the plate to the cylinder, means for stressing the movable member toward plate locking position, means for moving the movable member against the stressing means away from plate locking position, and means for locking the movable members in plate locking position.

13. In combination, a printing cylinder, margin bars on the cylinder, an arcuate printing plate, the straight edges of the printing plate and the longitudinal edges of the margin bars being constructed and arranged for interlocking engagement, spring actuated members operably supported by the cylinder for engaging and moving the plate to force the straight edges of the plate into locking engagement with the longitudinal edges of the margin bars thereby locking the printing plate to the cylinder.

14. In combination, a printing cylinder, margin bars on the cylinder, an arcuate printing plate, the straight edges of the printing plate and the longitudinal edges of the margin bars being constructed and arranged for interlocking engagement, spring actuated members operably supported by the cylinder for engaging and moving the plate to force the straight edges of the plate into locking engagement with the longitudinal edges of the margin bars thereby locking the printing plate to the cylinder, and means for locking the movable member in plate locking position.

15. In combination, a printing cylinder, margin bars on the cylinder, an arcuate printing plate, the straight edges of the printing plate and the longitudinal edges of the margin bars being constructed and arranged for interlocking engagement, movable members operably supported by the cylinder for engaging and moving the plate to force the straight edges of the plate into locking engagement with the longitudinal edges of the margin bars thereby locking the printing plate to the cylinder, means for stressing the movable member toward plate locking position, and means for locking the movable member in plate locking position.

16. In combination, a printing cylinder, margin bars on the cylinder, an arcuate printing plate, the straight edges of the printing plate and the longitudinal edges of the margin bars being constructed and arranged for interlocking engagement, movable members operably supported by the cylinder for engaging and moving the plate to force the straight edges of the plate into locking engagement with the longitudinal edges of the margin bars thereby locking the printing plate to the cylinder, means for biasing the movable member towards plate locking position, and means operable in opposition to the biasing means for moving the movable members from plate locking position.

17. In combination, a printing cylinder, margin bars on the cylinder, an arcuate printing plate, the straight edges of the printing plate and the longitudinal edges of the margin bars being constructed and arranged for interlocking engagement, movable members operably supported by the cylinder for engaging and moving the plate to force the straight edges of the plate into locking engagement with the longitudinal edges of the margin bars thereby locking the printing plate to the cylinder, means for biasing the movable member towards plate locking position, means operable in opposition to the biasing means for moving the movable members from plate locking position, and means for locking the movable member in plate locking position.

18. In combination, a printing cylinder, margin bars on the cylinder, an arcuate printing plate, the straight edges of the printing plate and the longitudinal edges of the margin bars being constructed and arranged for interlocking engagement, movable members operably supported by the cylinder for engaging and moving the plate to force the straight edges of the plate into locking engagement with the longitudinal edges of the margin bars thereby locking the printing plate to the cylinder, means for biasing the movable member toward plate locking position, means operable in opposition to the biasing means for moving the movable members from plate locking position, and means actuated by the rotation of the cylinder for locking the movable members in plate locking position.

WILLIAM F. HUCK. 50
